UNITED STATES PATENT OFFICE.

SOLOMON SHETTER, OF NEW CUMBERLAND, WEST VIRGINIA, ASSIGNOR OF
ONE HALF TO THOMAS J. GORLICK, ELMER J. SHETTER, AND ANDREW
M. SHETTER, ALL OF SAME PLACE.

OPEN LINK.

SPECIFICATION forming part of Letters Patent No. 251,958, dated January 3, 1882.

Application filed November 4, 1881. (No model.)

To all whom it may concern:

Be it known that I, SOLOMON SHETTER, of New Cumberland, in the county of Hancock and State of West Virginia, have invented a new and useful Improvement in Open Links, of which the following is a full, clear, and exact description.

Reference is to be had to the accompanying drawings, forming part of this specification, in which similar letters of reference indicate corresponding parts in all the figures.

Figure 1 is a perspective view of my improved link. Fig. 2 is a plan view, and Fig. 3 is an edge elevation, of the link.

The link is formed of the parts A and B, which are oppositely bent to form the hooks *a* *b*, which hooks are diagonally flattened or faced to fit upon each other, as clearly shown in Fig. 3. The straight end of the part A is flattened at right angles to the plane of the hook, as shown at *c*, and this flattened portion is perforated. The blunt end of the part B is

bent upward, as shown at *e*, so as to stand in the same plane with the hook *b*, and is reduced in size for a short distance, so as to pass through the perforation in the flattened portion *c* of the part A a sufficient distance to be headed over the flattened portion, as shown at *d*, to hold the two parts of the link together, but not rigidly, the part A being adapted to swing on the reduced portion of the part B as on a pivot for opening and closing the link.

Having thus described my invention, I claim as new and desire to secure by Letters Patent—

In a connecting-link, the combination, with the part B, provided with the hook *b* and the upturned end *e*, of the part A, provided with the hook *a* and the eye *c*, the said hooks being flattened diagonally, substantially as and for the purpose set forth.

SOLOMON SHETTER.
